Des. 223,008
Patented Feb. 22, 1972

223,008

LOCKING TAPE MEASURE OR SIMILAR ARTICLE

Robert J. Gould, Fairfield, Conn., assignor to Evans-Aristocrat Industries, Inc., Elizabeth, N.J.

Filed Oct. 12, 1970, Ser. No. 25,430

Term of patent 14 years

Int. Cl. D10—04

U.S. Cl. D52—1

FIG. 2

FIG. 4

FIG. 1

FIG. 5

FIG. 3

FIG. 6

FIG. 1 is a side elevational view of a locking tape measure or similar article showing my new design;

FIG. 2 is a top plan view thereof;

FIG. 3 is a bottom plan view thereof;

FIG. 4 is a left end elevational view of FIG. 1;

FIG. 5 is a right end elevational view of FIG. 1;

FIG. 6 is a rear side elevational view of FIG. 1.

I claim:

The ornamental design for a locking tape measure or similar article, substantially as shown.
